UNITED STATES PATENT OFFICE.

THOMAS J. WILSON, OF AUBURN, NEW YORK.

WRENCH.

SPECIFICATION forming part of Letters Patent No. 314,095, dated March 17, 1885.

Application filed September 19, 1884. (No model.)

To all whom it may concern:

Be it known that I, THOMAS J. WILSON, a citizen of the United States, residing at Auburn, in the county of Cayuga and State of

5 New York, have invented a new and useful Improvement in Wrenches, of which the following is a specification, reference being had to the accompanying drawings.

My invention relates to wrenches; and it 10 has for its object to provide improved means for holding a movable jaw at any desired adjustment upon the shank, which shall be simple and effective and easily operated, and by which the desired adjustment may be instantly 15 obtained.

With these ends in view the invention consists in the combination, with a shank carrying a fixed jaw at its end and having a series of teeth upon its upper side, of a movable jaw 20 adapted to slide upon said shank, and a pawl or stop for holding said movable jaw at any desired adjustment.

The invention further consists in the improved construction and combinations of parts 25 hereinafter fully described, and pointed out in the claim.

In the drawings, Figure 1 is a perspective view of a wrench constructed in accordance with my invention. Fig. 2 is a longitudinal 30 vertical section of the same, and Fig. 3 is a detail view of the pawl or stop detached.

In the accompanying drawings, in which like letters of reference indicate corresponding parts in all the figures, A represents the shank, 35 having at its front end a fixed jaw, B, which is preferably cast integral therewith. Upon the upper or top side of the shank A are provided a series of teeth, a, which incline forwardly. These teeth do not extend the entire 40 length of the shank, but leave a sufficient smooth space at the rear end to serve as a handle and to allow of the slipping of the movable jaw into place, while at the forward end a space is left which is the same width as the 45 movable jaw C. This movable jaw C is provided, as usual, with a passage or opening to receive the shank, upon which it is adapted to be moved, as before stated.

D represents a pawl or stop, which, as 50 shown, is provided with a series of teeth upon its under side, said teeth inclining in a direc-

tion opposite to those upon the shank A, so that all possibility of its slipping upon said shank, when the wrench is in use, will be prevented.

E represents bails, which are preferably of 55 spring brass or steel wire. One of said bails pivots the forward end of the stop or pawl to the forward end of the movable jaw, while the other bail connects the rear end of the stop or 60 pawl and the rear end of said movable jaw. These bails or loops pass through openings in the stop or pawl D, and have their ends bent inwardly to engage slots formed in the sides of the movable jaw, as shown. It will 65 be seen that as the stop is pivoted and weighted it will by its own weight drop into engagement with the teeth upon the upper side of the shank when the wrench is held in the position shown in Figs. 1 and 2; but should said 70 wrench be moved out of such position the stop would fall from engagement with the teeth and allow the jaw C to move toward the rear end of the shank.

I have mentioned that the bails or loops 75 were constructed of spring-wire, and to hold them in place and keep the stop in engagement with the teeth of the shank I have provided an outwardly-projecting pin or lug, d, upon each side of the movable jaw just above 80 the bail, connecting the rear end of the movable jaw with the rear end of the stop or pawl, and against the under side of which said bail is adapted to bear, being held in place thereby against any movement which might be caused 85 by the weight of the stop or pawl when the wrench was used in any other than a horizontal position.

In using the above-described wrench the 90 movable jaw is slid upon the shank until it reaches the nut or other object to be operated upon, the pivoted stop or pawl sliding upon the teeth upon the upper side of the shank; but as soon as such forward movement is stopped the movable jaw is locked against any rearward 95 movement and is held securely in place. To withdraw the wrench the pivoted stop or pawl is raised, which action is allowed by reason of the connecting-bails being made of spring-wire.

The raising of the stop or pawl is accomplished by means of a ring or loop, f, arranged

upon the upper side of the said stop or pawl, near the forward end thereof, though it will be obvious that other means than those shown and described may be employed.

5 It will be seen from the above description that a wrench constructed in accordance with my invention is simple in its construction, may be manufactured and supplied at a slight cost, that its operation is certain and effective, and 10 that by its use any desired adjustment of the jaws may be instantly obtained.

Having fully described my invention, what I claim as new, and desire to secure by Letters Patent, is—

15 As an improvement in wrenches, the shank or bar provided with a fixed jaw at one end, in combination with a sliding jaw having transverse elongated slots at the front and

rear ends, a pawl or stop, D, below the sliding jaw, and having teeth engaging teeth on the 20 shank, spring-bails E, pivoted on the front and rear ends of the pawl or stop, and having their other ends fitted in the slots of the sliding jaw, and pins or lugs d, projecting laterally from the sliding jaw in rear of one of the 25 bails, to provide an additional spring force for the same to retain the pawl or stop always in engagement, as set forth.

In testimony that I claim the foregoing as my own I have hereto affixed my signature in 30 presence of two witnesses.

THOMAS J. WILSON.
